UNITED STATES PATENT OFFICE.

ALEXANDER C. ELISHEWITZ, OF NEW YORK, N. Y.

DESIGN FOR BRAID.

Application filed October 19, 1927. Serial No. 23,801. Term of patent 14 years.

To all whom it may concern:

Be it known that I, ALEXANDER C. ELISHEWITZ, a citizen of the United States, residing at New York city, county of New York, and State of New York, have invented a new, original, and ornamental Design for Braid, of which the following is a specification, reference being had to the accompanying drawing, forming part thereof.

Fig. 1 of the drawing is a front or face view

of a piece of braid embodying my invention enlarged beyond the size of the braid as usually made.

Fig. 2 is a similar view of a piece of the same braid on a smaller scale.

I claim:

The ornamental design for braid, as shown.

In witness whereof, I have hereunto set my hand.

ALEXANDER C. ELISHEWITZ.
